UNITED STATES PATENT OFFICE.

JOSEPH H. STEICHEN, OF WOONSOCKET, SOUTH DAKOTA.

ENGINE-PRIMING APPARATUS.

1,249,234.

Specification of Letters Patent. Patented Dec. 4, 1917.

Application filed July 9, 1915. Serial No. 38,949.

To all whom it may concern:

Be it known that I, JOSEPH H. STEICHEN, a citizen of the United States, residing at Woonsocket, in the county of Sanborn and State of South Dakota, have invented new and useful Improvements in Engine-Priming Apparatus, of which the following is a specification.

This invention relates to engine priming apparatus being especially designed for use in connection with internal combustion engines of the multiple cylinder type, the object in view being to provide simple and reliable apparatus whereby priming liquid in predetermined quantities may be conducted to the combustion chambers of the several cylinders of the engine, without requiring the driver to leave his seat in the machine, thus enabling the cylinders to be primed one or more times until a starting of the engine is effected, the priming apparatus being especially useful in cold weather.

With the above and other objects in view, the invention consists in the novel construction, combination and arrangement of parts, as herein described, illustrated and claimed.

In the accompanying drawings:

Figure 1 is a side elevation partly in section illustrating the application of the priming apparatus of this invention to an automobile.

Fig. 2 is an enlarged detail fragmentary section illustrative of the valve arrangement whereby a predetermined or measured quantity of priming liquid is discharged to each cylinder of the engine.

A multiple cylinder engine is conventionally shown at A it being understood that the same is provided with the usual spark plugs as well as, priming cups 2, priming cup valves 3, and valve operating levers 4. All of the valve levers 4 extend in parallel relation to each other and are pivotally connected at 5 to a common operating rod 6 which extends rearwardly and is connected at 7 to a lever 8 shown as fulcrumed at 9 on the floor of the machine, the lever 8 enabling the operator to simultaneously open and simultaneously close all of the valves 3.

An elevated reservoir 10 for priming liquid is shown as secured to the dash 11 of the machine, 12 designating feed pipes leading from the bottom of the reservoir 10 to the priming cups 2 into which measured quantities of priming liquid are discharged as will hereinafter appear.

In the preferred embodiment of this invention, an upper series of valves 13 is arranged just under the bottom of the reservoir 10 while below the series of valves 13 is arranged a second or lower series of valves 14. Thus each of the feed pipes 12 has incorporated therein an upper valve 13 and a lower valve 14 in such spaced relation to each other as to leave a measuring chamber 15 formed by that portion of the pipe which lies between the valves 13 and 14. The valves 13 are provided with operating arms 16 in parallel relation to each other and having a pivotal or jointed connection to a common operating rod 17 which is pivotally connected at 18 to a hand lever 19. All of the valves 14 of the lower series are also provided with operating arms 20 arranged in parallel relation to each other and being connected to a common operating rod 21 which is pivotally connected at 22 to the lever 19 above referred to. The lever is fulcrumed at 23 about midway between the points 18 and 22 where the operating rods 17 and 21 connect with said lever. The general arrangement of the upper and lower series of valves 13 and 14 is such that when the lever 19 is drawn rearwardly or away from the dash 11, the upper valves 13 are moved to an open position while the lower valves 14 are moved to a closed position. This permits the priming liquid to fill the measuring chambers 15. When the lever 19 is again pushed forward to the limit of its movement, the valves 13 are moved to a closed position while the valves 14 are moved to an open position thus allowing a predetermined quantity of priming liquid to flow to the respective priming cups.

Each of the valves 13 and 14, in addition to the main through passage 24 thereof, is provided with an air vent passage or port 25 adapted to register at a suitable time with a port 26 in the valve casing, the said ports 26 providing for the flow of the priming liquid into the measuring chambers 15 and thence through the lower portions of the feed pipes 12 to the priming cups 2.

What I claim is:

The combination with a multiple cylinder engine having a priming cup for each cylinder, a rod operatively connected to the valve of each priming cup, a lever for operating said rod to open or close the priming cups simultaneously, a superimposed reservoir, a feed pipe for each priming cup leading

from said reservoir, a pair of primary and secondary valves in each pipe in spaced relation to each other, and a lever independent of the first named lever for simultaneously opening or closing the last named valves, all of the primary and secondary valves having air inlet ports.

In testimony whereof I affix my signature in presence of two witnesses.

JOSEPH H. STEICHEN.
